UNITED STATES PATENT OFFICE.

ALEXANDER R. KANNÉ, OF BROOKLYN, NEW YORK, ASSIGNOR TO KANNÉ AND BESSANT, INC., OF NEW YORK, N. Y., A CORPORATION OF NEW YORK.

DESIGN FOR A LAMP-SUPPORTING BRACKET.

Application filed February 4, 1928. Serial No. 25,210. Term of patent 7 years.

To all whom it may concern:

Be it known that I, Alexander R. KANNÉ, a citizen of the United States, residing at 1510 Carroll Street, Brooklyn, in the county of Kings and State of New York, have invented a new, original, and ornamental Design for a Lamp-Supporting Bracket, of which the following is a specification.

Fig. 1 is a view in side elevation of my ornamental design for a lamp supporting bracket and Fig. 2 is a top view thereof.

What I claim is:

The ornamental design for a lamp supporting bracket, substantially as shown.

ALEXANDER R. KANNÉ.
